UNITED STATES PATENT OFFICE

2,604,580

MEANS FOR SECURING LIGHT SOCKET CUPS TO SUPPORTING PLATES

Clyde D. McCann, Des Moines, Iowa

Application October 4, 1947, Serial No. 777,892

4 Claims. (Cl. 240—73)

19. *Leucosia* (Leucosia) *leucostoma* (Fabricius) (Fig. 19)

n is to pro- passagew

The principal object of my invention is to provide a means for rigidly securing a light cup bracket in spaced relationship to a wall or like back plate.

A further object is to provide a light fixture that is strong, easily assembled, and free from rattle during its useful life.

A still further object of my invention is to provide a rigid connecting link structure between the light cup and supporting back plate that is economical in manufacture, durable in use, and refined in appearance.

These and other objects will be apparent to those skilled in the art.

My invention consists in the construction, arrangement and combination of the various parts of the device, whereby the objects contemplated are attained as hereinafter more fully set forth, pointed out in my claims, and illustrated in the accompanying drawings, in which:

Fig. 1 is a side view of my construction in use.

Fig. 2 is a sectional view taken on line 2-2 of Fig. 1.

Fig. 3 is a sectional view taken on line 3—3 of Fig. 2 and more fully illustrates my invention. Fig. 4 is a perspective view of the two parts that

The art of lighting fixtures comprising a cup to hold the light socket, and a back supporting plate is old. The usual method of securing these two members together is by the use of a hollow bracket or tube. The objection to this construction, however, is that the structure is weak and subject to breakage, loosening, or bending during transit and when in use. I have overcome such objections as will hereinafter be appreciated

Referring to the drawings, I have used the numeral 10 to designate an ordinary light socket holding cup and the numeral 11 to designate its usual lamp shade or shield. The numeral 12 designates a wall, ceiling, or like supporting back plate. It is to such parts 10 and 12 that I use my invention and which I will now describe in detail. The numeral 13 designates a spacing outside collar ring having a front edge 14 and a rear shoulder 15, as shown in Fig. 4. This member is hollow and on the inner edge of the rear shoulder end 15 are two or more rearwardly extending sharp thin tongues 16, formed at time of manufacture. If the member is of oblong design as shown in Fig. 4, I recommend that a top and lower tongue be employed, as shown in Fig.

and lower tongue be employed as shown in Fig. 4. This member 13 is placed at time of manufacture between the cup 10 and plate 12, with the tongues 16 extending through the usual hole

2

passageway in the plate. The numeral 17 designates a hollow rivet extending through the cup 10, the collar ring 13, and the plate 12. This hollow rivet has its outside circumference substantially that of the inside circumference of the collar 13 and if the collar 13 is oblong in cross-section, this member should also be oblong in cross-section. When the hollow rivet is first installed at time of manufacture it is in the form shown in Fig. 4. However, by machinery its outer edge is rolled out and back on the inner side of the cup 10, and its rear edge rolled out and back on the inner side of the back plate 12. This last rolling and riveting action carries with it the bending and outward rolling of the tongues 16, as shown in Fig. 3. These tongues will therefore be bent and riveted between the inner side of the plate 12 and the outwardly bent rim head of the rivet 17. This will rigidly secure the spacing collar 13 to the back plate 12 and further make the entire construction stronger. The hollow rivet will rigidly secure the cup to the back plate with the collar 13 spaced between the cup and back plate. The edges of the collar will engage the outer wall of the cup and the outer wall of the back plate and the riveting of the rivet 17 will be so tight as to cause these edges to cut into the metal of both the cup and back plate. This construction makes for a very rigid and strong assembly. If desired, tongues 16 may be formed on either or both front and rear inner edges of the spacing collar 13. With my device the connection between cup and back plate will not bend or break down. One using my device may replace lamps or like in the socket cup without fear of bending or damaging the construction by the screwing action of removing or replacing incandescent light bulbs. As is well known, electric wiring will pass from the back plate into the cup socket, through the hollow rivet. Although I have described my device as particularly designed for light fixtures, obviously it may be used on any device where a rigid spacing connection is desired.

Some changes may be made in the construction and arrangement of the parts.

45 Some changes may be made in the construction and arrangement of my improved lighting fixture construction without departing from the real spirit and purpose of my invention, and it is my intention to cover by my claims, any modified forms of structure or use of mechanical equivalents which may be reasonably included within their scope.

I claim:

1. In combination with a light socket cup and
55 a supporting plate, a link securing means com-

prising, a hollow rivet extending through the wall of said cup and said plate, a spacing collar surrounding said rivet and between said cup and said plate, and a tongue on said spacing collar having a thickness substantially less than the thickness of said collar for providing a shoulder; said tongue extending through said plate and bent outwardly between the head of said rivet and the inner side of said plate; said bent up portion of said tongue and said shoulder being parallel and extending at each side of said plate, respectively.

2. In combination with a light socket cup and a supporting plate, a link securing means comprising, a hollow rivet extending through the wall of said cup and said plate, a spacing collar surrounding said rivet and between said cup and said plate, and a plurality of tongues on said spacing collar each having a thickness less than the thickness of said collar for providing shoulders; said tongues extending through said plate and bent outwardly between the head of said rivet and the inner side of said plate, and parallel with said shoulders, respectively.

3. In combination with a light socket cup and a supporting plate, a link securing means comprising, a hollow rivet extending through the wall of said cup and said plate, a spacing collar surrounding said rivet and between said cup and said plate, and a tongue on the inner marginal edge of the plate end of said collar extending through said plate and bent outwardly between the head of said rivet and the inner

5 side of said plate; said tongue having a thickness substantially less than the thickness of said collar for providing a shoulder for engaging the side of said plate opposite from the side of the plate engaged by said bent up portion of said tongue.

10 4. In a device of the class described, a member, a second member, a rivet extending through said first and second members, a spacing collar between said first and second members, and embracing said rivet, a tongue on one of the end edges of said collar extending into one of said members and bent between the inner side of that member and the head of said rivet; said tongue having a thickness substantially less than the thickness of said collar for providing a shoulder for engaging the side of said member through which said tongue extends at a point on the opposite side of which the member is engaged by the bent up portion of said tongue.

CLYDE D. McCANN.
